Primary Examiner — Robert M Spear*Assistant Examiner* — Ryan Harvey(74) *Attorney, Agent, or Firm* — Panitch Schwarze Belisario & Nadel LLP(57) **CLAIM**

The ornamental design for an exercise device, as shown and described.

DESCRIPTION

FIG. 1 is a left perspective view of an exercise device; FIG. 2 is a front elevational view thereof, a rear elevational view and top and bottom plan views being mirror images thereof; and, FIG. 3 is a left side elevational view thereof, a right side elevational view being a mirror image thereof. The broken lines in the figures are to illustrate environmental structure only and form no part of the claimed design.
